V. G. REUSCH

Des. 157,904

COATING APPLICATOR

Filed June 12, 1948

UNITED STATES PATENT OFFICE

157,904

COATING APPLICATOR

Verne G. Reusch, San Francisco, Calif.

Application June 12, 1948, Serial No. 146,930

Term of patent 14 years

(Cl. D9—6)

To all whom it may concern:

Be it known that I, Verne G. Reusch, a citizen of the United States and a resident of San Francisco, in the county of San Francisco and State of California, have invented a new, original, and ornamental Design for a Coating Applicator, of which the following is a specification, reference being had to the accompanying drawings, forming part thereof, wherein

I claim:

The ornamental design for a coating applicator, substantially as shown.

VERNE G. REUSCH.
